UNITED STATES PATENT OFFICE

2,438,766

SIDING TOOL

Milo Rifenberg, Constantine, Mich.

Application October 29, 1946, Serial No. 706,290

1 Claim. (Cl. 254—17)

1

This invention relates to what is known as a siding tool, and more particularly to a tool of the type used when applying sheathing or siding to studding. In the building trade, where it is necessary to use long runs of lumber, especially of the tongue and groove type, and to secure the same to studding, the problem presents itself of not only keeping the boards level, but tight before nailing. This is especially true today when so much lumber used in the building of homes, etc., is green and tends to warp and spread apart as it dries out.

The principal object of the present invention is to provide a new and improved tool for use when applying siding, or the like, to studding to enable the user to quickly secure the tool to the stud near to the point where he is about to place his nails, or other securing means, and hold the board or sheathing in tight relationship with the one immediately below same before securing the board to its supporting stud.

In modern building practice, especially when erecting homes or garages, it is standard practice to use the well-known two-by-four as a spaced support for the siding or sheathing used in this type of construction. I have provided a standard rigid member adapted to engage a two-by-four quickly which in turn eliminates the necessity of manually adjusting the same, which consumes too much time when engaged in modern production building practice.

The tool has but two moving parts and the user is not hampered by having to lock the tool in position, but has simply to use one hand to apply force to an adjacent lever while starting his nail into the siding and hence the studding.

The above and other objects will appear more fully from the following more detailed description, and from the drawing, wherein:

Fig. 1 is a perspective view showing the tool secured to a stud and the manner in which the siding engaging shoe engages the siding to be secured to its studding.

Fig. 2 is a side elevation of the tool per se,

Fig. 3 is a top plan view of the tool, and

Fig. 4 is a view of a shoe for use with the tool when the lumber used is not of the tongue and groove type.

Referring now to the drawing the numeral 10 designates a member for clamping or securing the tool to a stud 11. The member 10 is formed of a bar of steel having its end portions turned inwardly to form legs 12 adapted to slide over the ends of the ordinary two-by-four studding and the clamping member acts as a brace for

2

the tool per se. Rigidly secured, as by welding, or the like, to the flat side of clamping member 10, there is provided a flat bar 13 which extends out beyond the flat side of the clamping member 10, the same being adapted to pivotally support a lever 14 by means of a nut and bolt 15. A tongue engaging block or shoe 16 is provided, the same being morticed, as at 17, to allow lever 14 to pass therethrough and to be moved freely upon said lever to the position desired when in use. Block 16 is further grooved, as at 18, so that the groove may contact tongue 19 on board 20. The blocks are interchangeable, and, as shown best in Fig. 4 of the drawing, block 21 is identical with block 16 with the exception that in place of the groove, for use with tongue and grooved lumber, it is kerfed, as at 22, for use with lumber without the tongue and groove.

20 The manner in which the device is used is as follows:

When attaching siding to its studding the user simply secures his first run of boards down to the floor joists, and as he starts his next run 25 immediately above same, before driving his nails home into any one vertical stud, working from left to right, he secures the tool to the stud immediately above where the nails will enter the board being secured to said stud, clamping member 10 and legs 12 fitting neatly about the stud, as shown in Fig. 1, and if the board to be driven home is tongue and grooved, the type shoe shown in Figs. 1, 2 and 3 will be used, the shoe being slid upon lever 14 until it is in position to seat 30 upon tongue 19 and groove 18 engage the same. Bar 13 being rigidly secured to member 10 and lever 14 being pivotally mounted thereon as at 35 15, the nut and bolt 15 provide a fulcrum for lever 14 and, as pressure is brought to bear on the outer end of lever 14, by the user with one hand, the board to be nailed is forced tightly against the board immediately underneath, and while held in this position by means of shoe 16, the user drives at least one nail home through the 40 board and into the stud. He can then release the pressure on the lever 14, as the board 20 is set, and finish hammering home the desired number of securing nails. This procedure is followed 45 all along the board, the tool being moved from stud to stud as needed—the tool having either right or left action, the same may be used on either side of the stud. If the siding being applied is not tongue and grooved, the user simply changes shoes, using the type shoe 21 shown in Fig. 4 50 of the drawing, wherein the shoe contacting sur-

face is kerfed as at 22, which forms a flange abutting the edge of the board and forcing it downwardly as pressure is applied to lever 14.

There has been disclosed herein a simple, yet unique siding tool, simple of construction, yet strong and easy to use. It may be quickly moved from stud to stud by its user as desired. The wood contacting shoes are slidably mounted upon the pressure lever and are interchangeable quickly when needed for various types of siding.

While I have described and illustrated a satisfactory device that has proven highly successful in practical operation, it will be understood that the invention is not limited to specific constructional details shown and described, but that many changes, variations and modifications may be resorted to without departing from the principles of my invention.

I claim:

A siding tool of the character described for use in exerting pressure upon siding before securing same to its studs, comprising means for con-

tacting a stud, said means comprising a U-shaped member, a bar rigidly secured to said U-shaped member and extending outwardly therefrom, a lever pivotally mounted upon the outwardly extending portion of said bar, a morticed siding contacting shoe slidably upon said lever, said shoe being formed to contact said siding while pressure is being applied to said lever.
